FIG. 3

FIG. 4

Fig. 5

Fig. 1 is a fragmentary perspective view of a section of the interior of an airplane embodying my new design;

Fig. 2 is a similar fragmentary perspective view of a portion of the section shown in Fig. 1, taken from the opposite side of said section;

Fig. 3 is a horizontal cross section taken on the line 3—3 of Fig. 4 illustrating one of the seating sections which are repeated as indicated in Fig. 5;

Fig. 4 is a vertical cross section of the seating section illustrated in Fig. 3; and

Fig. 5 is a top plan view of an airplane embodying the seating section shown in Figs. 1 to 4, inclusive, said section being repeated as indicated.

The dominant feature of my design for an airplane resides in the section shown in full lines, said section be-

ing repeated throughout the length of the airplane as indicated in Figure 5.

I claim:

The ornamental design for an airplane, substantially as shown and described.
